ILLUMINABLE CANE FOR THE BLIND

John Velez, Jr., 732 N. Saint Andrews Place,
Hollywood, Calif. 90028

Filed May 12, 1967, Ser. No. 7,086

Term of patent 14 years

(Cl. D88—4)

FIG. 1.

FIG. 2.

FIG. 3.

FIG. 4.

FIG. 1 is a side elevation of an illuminable cane showing my new design;

FIG. 2 is an enlarged view similar to FIG. 1, but partially broken away to reveal the solid interior, side elevations from the remaining three directions at 90° to each other being identical except for the omission of the loop handle;

FIG. 3 is a top plan view of the cane; and

FIG. 4 is a bottom plan view.

The cane is formed of a light-conducting plastic and the shading indicates color contrast rather than any specific color.

I claim:

The ornamental design for a illuminable cane for the blind, as shown and described.
